H. F. SCHMIDT

HOTWELL EJECTOR

Filed Oct. 2, 1920

UNITED STATES PATENT OFFICE.

HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

HOTWELL EJECTOR.

Application filed October 2, 1920. Serial No. 414,313.

To all whom it may concern:

Be it known that I, HENRY F. SCHMIDT, a citizen of the United States, and a resident of Swarthmore, in the county of Delaware and State of Pennsylvania, have invented a new and useful Improvement in Hotwell Ejectors, of which the following is a specification.

My invention relates to heat conserving apparatus for power plants, and more particularly to that class of apparatus employed to utilize the heat of the exhaust steam discharged from the auxiliaries forming a part thereof.

The object of my invention is to provide means whereby the exhaust steam discharged from the auxiliaries may be utilized to operate an ejector removing condensate from the hot-well of the condenser and to heat the feed water supplied to the boilers.

A further object of my invention is to provide, in conjunction with auxiliary exhaust steam supplies, a high pressure supply, with automatic controlling means whereby motive fluid from the sources will be supplied in response to the demand or requirements.

I attain these objects by means of the apparatus shown in the accompanying drawing, in which the single figure shown is a diagrammatic illustration of my invention.

In the operation of power plants it is desirable to utilize all the energy available for effective work. In such a plant are usually turbines with ejectors and condensers associated therewith, feed water heaters, economizers, auxiliary pumps and engines all of which are designed to produce the highest efficiency in power production. With

the usual surface condenser having a hot-well and ejector associated therewith, I utilize the exhaust steam from partially condensing units as for example, exhaust steam from an ejector pump which is usually about 5-7 pounds pressure as the primary source of motive supply for the hot-well ejector of the surface condenser. In case of failure of the above source I employ the exhaust steam from non-condensing units such

as a boiler feed pump which exhausts at a higher pressure. I have further provided for a supply of live steam at boiler pressure, to operate the ejector upon failure of the auxiliary supplies, to furnish the requisite

amount of steam. In conjunction with the supplies enumerated I have associated means actuated by variations of pressure within the condenser and low pressure supply whereby the higher pressures are successively added to insure positive and efficient operation.

Referring to the drawing for a more detailed description of my invention, I indicate a surface condenser at 10, adapted to condense the exhaust steam from the main generating unit of a power plant. The condensate from the condenser 10 collects in a hot-well 11 from whence it is removed by means

of a condensate ejector 49 arranged to be operated by the exhaust steam from the partially condensing auxiliaries, by the exhaust steam from the non-condensing auxiliaries, and by live steam. Exhaust steam from

the partially condensing auxiliaries, ranging in pressure from five pounds to seven pounds absolute, is supplied through a conduit 12, the supply being controlled by means of a valve 13. The steam then passes through a conduit 14 to the chamber

15 of the condensate ejector 49. The steam nozzle 16 of the ejector expands the steam from the chamber 15 into the mixing chamber 17 where it mixes with the condensate in the hot-well 11, the resultant mixture being discharged through a conduit 18 to a feed-water heater 19.

An overflow 20 is provided for the ejector which discharges through conduit 21 into the condenser 10. The condenser is also provided with an air

ejector 22 which discharges through a conduit 23 into the feed water heater 19.

In normal operation of the condensate ejector, the steam from nozzle 16 entrains water from the hot well 11 and carries it along through the mixing chamber 17, where the steam is condensed in the water, so that a compact stream of water is discharged from the mixing chamber 17 into the diffuser conduit 18 at a considerable velocity. Under such conditions, there is no tendency for this high velocity stream of water to overflow into the chamber 20, but rather will the fluids in the chamber 20 be entrained in the rapidly moving stream of water.

Thus, air from the condenser 10 may be drawn through the conduit 21 and chamber 20 into the conduit 18 and discharged with the condensate into the heater

19, thereby assisting the ejector 22 in maintaining a high vacuum within the condenser.

In case the supply of exhaust steam from the partially condensing auxiliaries is not sufficient to operate the ejector properly, which may readily happen if certain of the partially condensing auxiliaries are shut down, an opposed pressure motor device 24 is provided which is adapted to open a balanced valve in the exhaust line from the non-condensing auxiliaries, thereby admitting steam from this source to the ejector. The exhaust steam from the non-condensing auxiliaries, ranging in pressure from two pounds to ten pounds gage, is supplied through a conduit 25, the supply to the ejector being controlled by means of a valve 26. The balanced valve 27 controlling the admission of steam from the non-condensing auxiliaries to the ejector is connected to the opposed pressure motor 24 through a rod 28. The supply conduit 25 is furthermore connected with the feed water heater 29 by a conduit 29, so that any exhaust steam not utilized by the condensate ejector may be used to heat the feed water for the boilers.

In case the combined steam from the partially condensing auxiliaries and the non-condensing auxiliaries is not sufficient to operate the ejector properly, the opposed pressure motor will then act to open a valve admitting live steam to the ejector. Live steam is supplied through a conduit 30, the supply being controlled by means of a valve 31. The balanced valve 32 controlling the admission of live steam to the ejector is connected through a lost link motion 33 and the rod 28 to the opposed pressure motor 24. The live steam after passing the valve 32 enters the chamber 34 where it exerts pressure against the face 35 of the movable nozzle 36, thereby forcing it up against the nozzle 16. The nozzles 36 and 16 then act as one nozzle to expand live steam into the mixing chamber 17.

The opposed pressure motor 24 comprises a single cylinder 37 provided with a piston 38. The chamber 39 above the piston is connected to the supply conduit 14 by means of a conduit 40 and in a similar way the chamber 41 below the piston is connected to the condenser 10 by means of the conduit 42.

The heated feed water from the feed water heater 19 discharges through a conduit 43 into a boiler feed pump 44. The pump 44 then forces the feed water through a conduit 45 to an economizer 46 located in a flue 47, from which it is discharged through a conduit 48 to the boilers. The condensate which is employed as boiler feed water is thus successively heated in the heater 19 by steam from the auxiliaries through pipe 25

and by steam and air from the ejector 22 through pipe 23, and then further heated by furnace gases in the economizer 46.

Under normal conditions, with all the partially-condensing auxiliaries running, the exhaust steam from this source is sufficient to operate the condensate ejector. In case the steam from this source is not sufficient to operate the condensate ejector properly, the pressure in the condenser builds up. This increase in pressure is transmitted through the conduit 42 to the chamber 41 below the piston 38, with the result that the increase in pressure on the bottom of the piston 38 will tend to open the balance valve 27, admitting steam from the non-condensing auxiliaries to the ejector in addition to the steam from the partially-condensing auxiliaries. In case this combined supply of steam is insufficient to operate the ejector properly, further increase in pressure in the condenser exerts a greater upward force on the piston 38, thereby opening the balance valve 32 in the live steam line. Live steam will then enter the chamber 34 and acting on the face 35 of nozzle 36, forces the nozzle up against the nozzle 16. An increase in the steam supply through the conduit 14 increases the pressure in the conduit 14, this pressure being transmitted through the conduit 40 to the chamber 39 of the balance valve. This increase in pressure forces the piston 38 down first closing balance valve 32 and then balance valve 27 in turn. The ejector then operates under normal conditions.

While I have shown my invention in but one form, it will be obvious to those skilled in the art that it is not so limited but is susceptible of various other changes and modifications, without departing from the spirit thereof and I desire, therefore, that only such limitations shall be placed thereupon as are imposed by the prior art or as are specifically set forth in the appended claims.

What I claim is:—

1. In combination with a condenser, an air ejecting device and a condensate-ejecting device associated therewith, a feed-water heater connected to the air and condensate ejecting devices, and a feed water economizer connected to the heater, whereby condensate discharged from the condenser receives heat from the air ejecting device and from the economizer.

2. In combination with a condenser, a condensate-removing device comprising an ejector and an overflow therefor, said overflow being connected to the upper portion of the condenser, whereby, in normal operation, air is withdrawn thereby from the condenser, a plurality of sources of motive fluid of different pressures associated with the ejector, and means controlling the supply of

motive fluid to said ejector responsive to pressure conditions in the condenser.

3. In combination with a condenser, a condensate ejecting device, a plurality of fluid supply sources associated with the ejecting device, and control means for one of the supply sources responsive to pressure differences in the condenser and the other supply source.

10 4. In combination with a condenser and feed water heater, a hot-well for the condenser, an ejector adapted to withdraw condensate from the hot-well, an overflow chamber at the discharge end of the ejector, 15 a conduit leading from the overflow chamber to the top portion of the condenser, a conduit leading from the overflow chamber to the feed-water heater, and means responsive to the pressure within the condenser for controlling the supply of motive fluid to the 20 ejector.

5. In combination with a condenser, a hot-well, an ejector adapted to withdraw condensate from the hot-well, an overflow chamber having communication with the top of the condenser, three motive fluid supply conduits for the ejector adapted to conduct fluid at different pressures, automatic pressure means for controlling the flow of fluid 25 through two of the conduits responsive to the pressure existing within the condenser and the pressure within the low-pressure conduit.

30 6. In combination with a condenser and a feed-water heater, a condensate ejector adapted to remove condensate from the condenser and discharge it into the heater, a plurality of sources of motive fluid for the ejector at normally different pressures, and means controlling the passage of fluid from 35 one of said sources responsive to pressure conditions existing within the condenser and within the other source.

7. In combination with a condenser, feed- 40 water heater and economizer, a condensate ejector adapted to withdraw condensate from the condenser and discharge it into the feed-water heater, an air ejector adapted to withdraw non-condensable vapors from the 45 condenser and supply them to the heater and means to supply fluid from the heater to the economizer.

50 8. In combination with a condenser, a feed-water heater, a condensate ejector for withdrawing condensate from the condenser and supplying it to the feed-water heater including an expansion nozzle, a steam chamber connected to said nozzle, conduits adapted to be connected to partially condensing and non-condensing power units and communicating with the chamber, a high-pressure conduit, means carried by the high-pressure conduit and movable upon admission of high-pressure steam to afford 55 direct communication between the expansion

nozzle and the high-pressure conduit and close communication between the chamber and the first conduits, valve means carried by the non-condensing and high-pressure conduits, and means to actuate said valve 70 means in response to pressures existing within the condenser and within said non-condensing conduit whereby motive fluid is admitted in response to condenser requirements.

75 9. In combination with a condenser, a hot-well connected to the condenser, a condensate ejector associated with the hot-well and including a motive fluid nozzle, low, intermediate, and high-pressure motive fluid 80 supplies adapted to communicate with the nozzle, and means for controlling the passage of fluid from the intermediate and high-pressure supplies responsive to pressures existing within the condenser and 85 within the low-pressure supply.

10. In combination with a condenser, a hot-well connected to the condenser, a condensate ejector associated with the hot-well and including a motive fluid nozzle, low, 90 intermediate and high pressure motive fluid supplies adapted to communicate with the nozzle and means for controlling the passage of fluid from the intermediate and high pressure supplies, including a motor device 95 actuated by the difference in pressure existing in the condenser and the low pressure supply.

100 11. In combination with a condenser and an economizer, a hot-well for the condenser, an ejector adapted to withdraw condensate from the hot-well and discharge it to a feed-water heater, a pump associated therewith to force the condensate to an economizer, a plurality of ejector feed supply sources at low, intermediate and high pressures, a valve control means for the pressure sources, a conduit leading from condenser to said means and a conduit leading from said means to the low and intermediate supply sources whereby the difference of pressure in the condenser and the low and intermediate pressure sources actuate the valve control means.

105 115 12. In combination with a condenser, feed-water heater and economizer, a condensate ejector adapted to withdraw condensate from the condenser and to discharge it into a feed-water heater, an air ejector adapted to withdraw non-condensable vapors from the condenser and to supply them to the feed-water heater and a conduit to supply fluid from the heater to the economizer, high, intermediate and low pressure supply source to condensate ejector having pressure control means for controlling the respective supply sources in successive operation.

120 125 130 13. In combination with a condenser, hot-well and condensate ejector, motive fluid

supply means for the ejector, comprising low, intermediate, and high pressure supplies, said low and intermediate supplies arranged to pass through a common element 5 and means responsive to pressure differences existing between the condenser and said element for controlling the passage of fluid from said intermediate and high pressure supplies.

10 14. In combination with a condenser, a hot-well, a feed-water heater, and condensate ejector to withdraw condensate from the hot-well and deliver it to the feed-water heater, means comprising a low-pressure 15 conduit, an intermediate pressure conduit, a high-pressure conduit, and means for connecting the conduits with the condensate ejector, successively acting valves within intermediate and high pressure conduits 20 actuated by pressure differences within the condenser and low and intermediate pressure sources.

15 15. In combination with a condenser, a feed-water heater, a condensate ejector for 25 withdrawing condensate from the condenser and supplying it to the feed-water heater including an expansion nozzle, a steam chamber connected to said nozzle, conduits adapted to be connected to condensers and non-condensing power units 30 and communicating with the chamber, a high-pressure conduit, an intermediate pressure conduit and a low pressure conduit and a pressure responsive means operated 35 by the pressure in the low and intermediate pressure conduits whereby a constant supply of motive fluid is maintained in the steam chamber at the expansion nozzle.

16. In combination with a condenser, a 40 hot-well, a feed-water heater and a condensate ejector adapted to withdraw condensate

from the hot-well and supply it to the feed-water heater, low, intermediate and high pressure conduits for supplying the condensate ejector with motive fluid, a pressure 45 control means operated by the difference of pressure within the condenser and supply sources, said means operating a valve in the intermediate and high pressure supply conduits whereby the ejector is made positive 50 in operation by the admission of motive fluid in three successive stages from the low, intermediate and high pressure sources respectively.

17. In combination with a condenser, a 55 condensate ejector for said condenser, means for supplying steam to said ejector, and means associated with said steam supplying means and responsive to the pressure within the condenser for regulating 60 the amount of steam delivered to the ejector.

18. In combination with a condenser, a condensate ejector for said condenser, means for supplying steam to the ejector at 65 different pressures and means associated with said steam supplying means and responsive to the pressure within the condenser for regulating the pressure of steam delivered to the ejector. 70

19. In combination with a condenser, a condensate ejector for said condenser, means for supplying steam to the ejector at different pressures and means associated with said steam supplying means and responsive to increasing pressures within the condenser for delivering steam to the ejector at increasingly higher pressures. 75

In testimony whereof, I have hereunto subscribed my name this 28 day of September 1920.

HENRY F. SCHMIDT.
